DESIGN FOR A LIQUID EDUCTOR

Philip Berman, New York, N. Y.

Application December 18, 1944, Serial No. 116,969

Term of patent 14 years

(Cl. D65—1)

To all whom it may concern:

Be it known that I, Philip Berman, a citizen of the United States, residing in New York city, county and State of New York, have invented a new, original, and ornamental Design for a Liquid Eductor, of which the following is a specification, reference being had to the accompanying drawing, forming part thereof.

Figure 1 is a side view of the liquid eductor showing my new design; and

Figure 2 is a top plan view thereof.

I claim:

The ornamental design for a liquid eductor, as shown.

PHILIP BERMAN.
